D 16,973

UNITED STATES PATENT OFFICE.

WILLIAM N. PEAK, OF BROOKLYN, NEW YORK.

DESIGN FOR WALL-PAPER.

SPECIFICATION forming part of Design No. 16,973, dated November 2, 1886.

Application filed August 20, 1886. Serial No. 211,454. Term of patent 3½ years.

To all whom it may concern:

Be it known that I, WILLIAM N. PEAK, of Brooklyn, in the county of Kings and State of New York, have invented a new and original Design for Wall-Paper, of which the following is a specification.

The nature of my design is fully represented in the accompanying print, to which reference is made.

10 The design consists, principally, of a kaleidoscopic star, A, having a Greek-cross center, a, and a border, b, surrounding said center. Radiating from the border b are the blocks c, over each of which is an arch, d, within which is an angle, e. Surrounding the arches d are the blocks f, forming a broken circle, and around the blocks f appear the block-stars g. Between the stars A appear the block-stars h, and also the larger stars, B, the latter composed of a center piece, i, surrounded by nu-

merous small Greek crosses, h', the whole surrounded by the scalloped or many-pointed border k, as shown in the accompanying print.

I claim—

1. The design for wall-paper herein shown and described, the same consisting of a star composed of a Greek-cross center, a, and radiating blocks c, and arches d beyond the blocks.

2. The design for wall-paper herein shown and described, the same consisting of a large star and smaller star, B, composed of a center, i, numerous crosses, h', and a surrounding border, k.

3. The design for wall-paper, substantially as shown in the accompanying print.

WILLIAM N. PEAK.
